UNITED STATES PATENT OFFICE.

WILLIAM A. WHITNEY, OF ROCKFORD, ILLINOIS, ASSIGNOR TO WHITNEY METAL TOOL COMPANY.

HAND METAL-SHEARS.

1,065,753.

Specification of Letters Patent. Patented June 24, 1913.

Application filed February 17, 1912. Serial No. 678,254.

To all whom it may concern:

Be it known that I, WILLIAM A. WHITNEY, a citizen of the United States, residing at Rockford, in the county of Winnebago and State of Illinois, have invented a new and useful Hand Metal-Shears, of which the following is a specification.

This invention relates to shears, such as are specially intended for cutting metal or performing other heavy work, although the principles of the present invention may be applied to lighter forms of shears, if desired.

The objects of the invention are, first, to adapt the shears to be folded into small compact forms when not in use, whereby to render them readily portable; second, to provide means for supporting the guiding handle of the shears so as to dispose it the proper distance above the surface on which the work is being performed; third, to effect self-sharpening and a ready replacement of the cutting portions of the shears; fourth, to provide for the adjustment of the blades or cutting portions toward each other; and fifth to shape the edges of the cutting portions in such manner as to produce the best results.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing forming a part of this specification, Figure 1 is a side elevation of a pair of shears constructed in accordance with the present invention, the operating handle being thrown upward to its extreme limit and the guiding handle being in alinement with the straight or under blade of the shears, the supporting means being shown in position to hold the guiding handle in raised position; Fig. 2 is a view similar to Fig. 1 showing the operating handle thrown downward to the point

where its movement is checked by the stop 50 on the guiding handle; Fig. 3 is a plan view of the shears, part of the handles being broken away; Fig. 4 is a view in side elevation showing both of the handles folded underneath the blades so as to render the 55 device readily portable; Fig. 5 is a section on the line 5—5 of Fig. 1 showing the means for limiting the downward movement of the operating handle; Fig. 6 is a section on the line 6—6 of Fig. 3 showing the handle fulcrum; Fig. 7 is a detail view of the device for locking the guiding handle in alinement with the straight blade; and Figs. 8 and 9 are views of the detachable cutting members having their contacting faces concaved to 65 provide for self-sharpening, means being shown for adjusting the cutting edges of said members toward each other.

Like reference numerals indicate corresponding parts throughout the several figures of the drawing.

The shears of the present invention comprise a lower or straight blade 1 and an upper or shearing blade 2. The lower blade 1 is provided with a straight cutting edge 3, 75 and the upper blade 2 with a curved or shearing edge 4. The straight blade 1 and shearing blade 2 are connected with each other by the blade fulcrum 5. The straight blade 1 is provided with a handle or guiding 80 member 6. The guiding handle 6 is pivotally connected with the straight blade 1 by means of the handle fulcrum 7. The pivotal connection between the guiding handle 6 and the lower or straight blade 1 is what 85 may be termed an elbow connection, that is a connection which will fold downward from the position shown in Fig. 1 to that shown in Fig. 4, but which will not fold upward. The preferred means for providing this elbow connection is best shown in Fig. 3 of the drawing wherein it will be seen that the rear end of the straight blade 1 is enlarged, as indicated at 9, a slot 10 being formed in the enlargement 9.

Fitting snugly into the slot 10 is an extension 11 of the guiding handle 6. The guiding handle 6 is formed with a shoulder

12 which abuts against a complementary shoulder on the rear end of the blade 1, as shown in Fig. 3. Moreover, the end of the extension 11 abuts against the end of the slot 10 and these abutting shoulders, in connection with the fact that the blade fulcrum 7 extends through the blade 1 and the handle 6 at a point below the said abutting shoulders, provide a joint which can fold 10 downward but not upward. It is to be understood, however, that any other suitable form of elbow joint can be employed.

For the purpose of preventing the hand of the operator from being pinched between the blades, the guiding handle 6, intermediate its ends, is bent slightly, as indicated at 15 and the handle portion 15 is disposed at a slight downward angle terminating at its lower end in a support 16 which rests upon the surface on which the work is being performed. It will be obvious that during the cutting operation, the shears are supported at their rear ends by the support 16, and at their forward ends by the lower or straight 20 blade 1, as shown clearly in Fig. 1. The specific means for preventing the operating handle 17 from being thrown downward far enough to strike the handle portion 15 of the guiding handle 6 preferably consists of 25 a spring operated stop 18 shown in Figs. 1 and 5 of the drawing. The stop 18 is thrown normally into operative position by the spring 19 and may be retracted either by the finger piece 20 or the beveled portion 30 21. The unbeveled side of the stop 18 is presented upward in Fig. 1 so as to engage the operating handle 17 and limit its downward movement.

When folding the two handles, as hereinafter described, it is necessary to retract the stop 18 by the finger piece 20 in order that the operating handle 17 may pass slightly beyond the guiding handle, as shown in Fig. 4. The beveled side 21 of the 45 stop permits the operating handle to be subsequently thrown back into its uppermost position by riding over the stop 20, after which said stop snaps outward and resumes its normal function of limiting the downward movement of the operating handle.

The operating handle 17 is mounted on the handle fulcrum 7. For the purpose of bracing the handle fulcrum 7 and the blade fulcrum 5, a bracing plate 24 extends from 55 one of said fulcrum members to the other. The bracing plate 24 is disposed on the outside of the shearing blade 2, as shown clearly in Figs. 1 and 3. Suitable nuts are mounted on the blade and handle fulcrums 60 5 and 7, as shown clearly in the drawing.

The means for communicating the movement of the operating handle 17 to the shearing blade 2 with greatly increased force or leverage, preferably includes the oper-

ating teeth 26 mounted or formed on the 65 operating handle 17 adjacent the fulcrum 7 thereof, the teeth 26 engaging with similar teeth 27 formed on a transverse head 28 which is mounted on the rear end of the shearing blade 2. By moving the operating 70 handle 17 downward, toward the guiding handle 6, it will be obvious that the rear end of the shearing blade 2 will be swung upward and the cutting or shearing edge 4 will be moved downward against the 75 straight cutting edge 3, so as to shear the metal held therebetween. It will be observed from Fig. 1 that the supporting member 16 of the guiding handle 6, by holding said guiding handle in raised position, provides a clearance space for the head 28 of the shearing blade 2, so that said head or toothed portion will be able to move downward to the full limit without being retarded by striking against the surface on which 85 the work is being performed.

It will be obvious that the shears as shown in Figs. 1 and 2 can be readily folded into the position shown in Fig. 4 by swinging both of the handles downward on the handle 90 fulcrum 7 until they assume the position shown in Fig. 4, beneath the blades 1 and 2.

I prefer to employ means for locking the guiding handle 6 in alignment with the straight blade 1, so that the joint between 95 the handle and the blade will not accidentally break upward. I also prefer to use the operating handle 17 as a means of controlling the locking device for the guiding handle 6. The means for accomplishing 100 this result will now be described. Extending through the rear end of the straight blade 1 is a spring operated bolt 30 which, as shown in Fig. 6, is adapted to be forced, against the action of the spring 31, into a 105 socket 32 formed in the end of the guiding handle 6. So long as the bolt 30 is forced into the socket 32, the guiding handle 6 is locked in alignment with the straight blade 1. It is to be explained that when the 110 shears are in operation, the operating handle 17 is never thrown as high as it is shown in Fig. 1. The operating handle 17 is only moved to this upward limit for the purpose of releasing the bolt 30, whereby to unlock 115 the guiding handle 6, and thus permit the shears to be folded. In the position shown in Fig. 1 the bolt 30 is held by the spring 31 out of engagement with the socket 32 in the guiding handle 6. By drawing the 120 handle 17 backward a slight distance, said handle rides over a beveled nose 33 on the bolt 30, as shown in Figs. 6 and 7, and thus forces said bolt into the socket 32, against the action of the spring 31, and holds it 125 positively in such position during all of the time that the operating handle is used to operate the shears. When it is desired to

fold the shears, the operating handle 17 is first thrown upward into the extreme position shown in Fig. 1, so that the portion of said operating handle adjacent the handle 5 fulcrum 7 moves out of contact with the beveled nose 33 of the pin 30. The spring 31 then throws said pin 30 out of the socket 32 in the guiding handle 6 and said guiding handle may then be folded downward, after 10 which the operating handle 17 can likewise be folded downward into the position shown in Fig. 4. As before explained, after the operating handle 17 has been moved downward and then upward, almost into the folded 15 position shown in Fig. 4, it strikes against the unbeveled side of the stop 18 in Fig. 5, and it is necessary to retract said stop by the finger piece 20 in order to permit the operating handle 17 to move upward the remainder of the way so as to lie snugly 20 in the position shown in Fig. 4.

In assembling the shears for use, the operating handle 17 in Fig. 4 is first drawn downward. During this movement it rides 25 readily over the beveled face 21 of the stop 18. The operating handle 17 is then thrown entirely around into the extreme position shown in Fig. 1, thus permitting the locking member 30 to be thrown outward by its 30 spring 31. The guiding handle 6 can then be swung from the position shown in Fig. 4 to that shown in Fig. 6. The operating handle 17 is then swung a slight distance to the left in Fig. 1 so that it engages the beveled 35 nose 33 of the pin 30 and throws it into the socket 32, thus locking the guiding handle 6 in alignment with the straight blade 1 and holding it positively locked in that position until the operating handle 17 is again 40 thrown backward into its extreme upward position preparatory to folding the shears.

In Figs. 8 and 9 of the drawing are shown the details of the improved detachable cutting members 35 and 36 which are set into 45 rabbeted portions 37 of the blades 1 and 2. The contacting faces of the cutting members 35 and 36 are concaved, as indicated at 38, whereby to provide for self-sharpening of the cutting edges when the shear members 50 are drawn apart.

The means for holding the blades in position and for adjusting them from time to time consists of the large set screws 40 which extend through the blades 1 and 2 and engage the rear or non-cutting edges of the cutting members 35 and 36. Extending through the blades 1 and 2 are blind set screws 41 which engage the outer faces of the cutting members nearer their cutting 55 edges than the set screws 40. By screwing the blind set screws 41 inward, the cutting portions of the cutters are forced or set toward each other so as to make up for any wear thereon.

By means of the foregoing improved self-sharpening means and the combination of the straight cutting edge 3 with the curved or shearing edge 4, the operation of the device is found to be very satisfactory.

What is claimed as new is:

1. Shears having a pair of handles both adapted to be folded against the same side of the shears.

2. Shears having folding handles, one of said handles being adapted to be locked in alignment with one blade of the shears.

3. Shears comprising blades, handles, a blade fulcrum, a handle fulcrum securing both handles to one of said blades, the other of said blades being operatively connected with one of said handles.

4. Shears comprising blades, a guiding handle, an operating handle, a blade fulcrum, a handle fulcrum connecting both of said handles with one of said blades, means for locking said guiding handle in alignment with one of said blades, and an operative connection between said operating handle and the other of said blades.

5. Shears comprising upper and lower blades, guiding and operating handles the guiding handle being bent away from the operating handle and said operating handle being straight, a blade fulcrum, a handle fulcrum connecting both of said handles to the lower blade, an operative connection between the operating handle and the upper blade, and a supporting member connected with the guiding handle, for the purpose specified.

6. Shears comprising upper and lower blades, a bent guiding and a straight operating handle, a blade fulcrum, a handle fulcrum connecting both of said handles to the lower blade, an operative connection between the operating handle and the upper blade, the guiding handle being bent adjacent the grip and having a supporting member extending downward therefrom, for the purpose specified.

7. Shears comprising blades, a guiding and an operating handle, a blade fulcrum, a handle fulcrum connecting both of said handles to one of said blades, the operating handle being operatively connected with the other blade, and means controlled by the operating handle for locking the guiding handle in alignment with one of the blades.

8. Shears comprising blades, a bent guiding and a straight operating handle, a blade fulcrum, a handle fulcrum connecting both of said handles to one of said blades, the operating handle being operatively connected with the other blade, and means on one of said handles for limiting the downward movement of the operating handle.

9. Shears comprising blades, handles, a blade fulcrum, a handle fulcrum extending

through both the handles and one blade, both handles being foldable relatively to the blades.

10. Shears comprising blades, handles, a 5 blade fulcrum, a handle fulcrum extending through both the handles and one blade, both handles being foldable relatively to the blades, one of the handles being foldable only in one direction.

10 11. Shears comprising a guiding handle having a downwardly extending grip and a supporting member connected with said grip, a blade connected with said guiding handle

by a folding joint, a second blade fulcrumed on said first blade, a folding operating 15 handle pivotally connected with said guiding handle and first blade, and an operating connection between said operating handle and said second blade.

In testimony that I claim the foregoing 20 as my own, I have hereto affixed my signature in the presence of two witnesses.

WILLIAM A. WHITNEY.
